MANUFACTURE OF FILMS, FOILS, AND THE
LIKE CONTAINING CELLULOSE DERIVA-
TIVES

Henry Dreyfus, London, England

Application August 25, 1933, Serial No. 686,739
In Great Britain September 9, 1932

9 Claims. (Cl. 18—15)

This invention relates to improvements in cellulose derivative products and particularly to the manufacture of films, sheets, foils, for example, those used for wrapping purposes, and like materials from solutions of cellulose acetate or other cellulose ester or ether by wet coagulation processes.

I have discovered that particularly good results are obtained in the manufacture of films, which term is to be understood as including foils, sheets and the like, from solutions of cellulose acetate or other cellulose derivative when the extrusion orifice or other shaping device is situated outside the coagulating medium, and according to the present invention, therefore, films having a basis of cellulose derivatives are produced by causing a solution of a cellulose derivative to issue from a suitable shaping device which is outside the coagulating medium, and then passing the film into such medium.

Any suitable means of shaping the film-forming solution may be employed. Thus it may be passed through an elongated slit or between rollers, and the distance of such shaping device from the coagulating medium may be quite small, for example 1 or 2 inches or it may be greater, for example, 6 to 8 inches or even more. After issuing from the orifice the film is preferably received upon a suitable supporting surface, for example a band or drum, and this surface may be wholly or partially immersed in the coagulating liquid. By causing the film to enter the coagulating medium before contacting with the supporting surface the advantages, described in British Patent No. 405,692, resulting from contact of the coagulating medium with both surfaces of the product may be obtained.

Since the films produced according to the process of the present invention are in general very thin and fragile, and are thus liable to be disturbed in their passage from the shaping orifice to the supporting surface or liquid medium by air currents, it is advantageous to surround the shaping orifice with a shield in order to isolate substantially the surrounding atmosphere. Such a shield may consist merely of metal or other sheets surrounding the shaping orifice and extending downwards towards the supporting surface or the surface of the liquid, but preferably a casing is employed in which the shaping orifice is situated, the bottom of this casing either dipping into the coagulating medium or making close contact with the surface of the supporting band, drum or the like. Further, since the rotation of the supporting surface in the coagulating me-

dium may tend to set up liquid currents which also disturb the relatively fragile film, it is advantageous in the case when the film passes through the liquid medium before contacting with the supporting surface to surround it in this medium with a protecting shield. Such shield may if desired be a continuation of the casing surrounding the film in its passage from the shaping orifice to the surface of the coagulating medium and may be formed in one piece with it. 10

When such a shield is employed means will of course be adopted to ensure that the medium in the neighbourhood of the film is maintained in such a condition that satisfactory coagulation is obtained, e. g. by maintaining a slow circulation 15 of the medium in the vicinity of the product.

In order to prevent a too rapid evaporation of any volatile solvent from the film after issuing from the shaping orifice and before its entry into the coagulating bath, it may be desirable to 20 maintain a relatively high concentration of solvent in the atmosphere surrounding the film. Thus when the shaping orifice is contained in a casing as described in the preceding paragraph, the atmosphere in such casing may be maintained 25 substantially saturated with solvent vapour, for example, by the presence inside the casing of a vessel containing solvent and/or a fabric or other fibrous material or a porous material as for example, pumice, saturated or substantially saturated 30 with solvent. Suitable means may be provided for maintaining the fabric or other extended surface in a saturated state, as for example, by immersing a portion of it in a bath containing solvent or by allowing solvent to drip onto 35 it through suitable orifices. If, however, it is desired that at least a partial coagulation of the film shall take place before its entry into the coagulating medium, means may be provided by 40 which a current of air or other evaporative medium is passed in contact with the film during its passage from the shaping orifice to the coagulating medium, for example by passing a current of air through the casing surrounding the film, or the film may be sprayed with a coagulating medium. Moreover, the use of both these means 45 in conjunction is of course not excluded.

If desired, a stretch may be imparted to the films during their production. Thus the film may be taken up on a drum or other support travelling at a speed greater than that at which the film issues from the shaping device, or, alternatively, the films may be stretched laterally and/or transversely by means of the apparatus described in U. S. Patent No. 2,034,716. 55

Any suitable solvent may be employed for forming the solution of the cellulose acetate or other cellulose derivative, as, for example, relatively low boiling solvents or solvent mixtures such as 5 acetone, acetone and alcohol, methylene-ethylene-ether and mixtures of methylene or ethylene chloride with ethyl or methyl alcohol, or of methyl or ethyl acetate with methyl or ethyl alcohol. Higher boiling solvents may also be used, 10 for example, methyl ethyl ketone, dioxane, diglycerol tri-ether, diacetone alcohol, esters or ether-esters of olefine and poly-olefine glycols, for example, glycol mono-acetate or methyl glycol mono-acetate, ethyl lactate, and homologues and 15 substitution products of methylene ethylene oxide and dioxane, as for example the esters and ether-esters of dioxane-dicarbinol. Mixtures of solvents, e. g. a mixture of a low and higher boiling solvent, may also be employed. The film-forming solutions may also contain diluents, for 20 example water, glycol, glycerol or other hydroxy compound, benzene, toluene, kerosene, hexahydro-benzene or other aromatic aliphatic or alicyclic hydrocarbon, and halogenated hydrocarbons, for example, tetrachlorethane and dichlorethylene. High boiling solvents or plasticizers for the 25 cellulose derivative may also be incorporated in the film-forming solutions, and examples of such substances are the acetins, alkyl phthalates, for example diethyl phthalates, and arylsulphonamides, as for example the monomethylated or ethylated xylene sulphonamides.

The coagulating baths employed may be aqueous or organic or may be aqueous solutions of organic compounds, and if desired coagulating baths containing solvents or softening agents for the cellulose derivative may be used. In this connection reference is made to U. S. Patents Nos. 1,465,994, 1,467,493 and 2,025,730 and British Patents Nos. 340,324, 340,325, 340,326, 343,062, 378,858 and 380,819. Coagulating baths containing the same solvent as that present in the film-forming solution, as is described in British Patent No. 405,676, may be advantageously employed. Again, 35 the coagulating bath may be one in which the solvent of the film-forming solution is immiscible or is miscible only in certain proportions as described in British Patent No. 407,673. Thus, for example, an acetone solution of cellulose acetate 40 may be coagulated in a bath consisting of or containing benzine, kerosene or other paraffin hydrocarbon. Again, coagulating media containing glycerine, sugars or other polyhydroxy compounds 45 may be employed, see for example British Patent No. 406,986. The use of solutions of inorganic salts, for example, sodium chloride or calcium chloride, as is described in British Patent No. 406,337, has, however, been found to be of particular value in connection with the present process. 50

The period of contact of the film with the coagulating media may be such that when they issue therefrom they contain substantially no residual solvent, in which case they may be directly dried, with or without previous washing or other treatment to remove any adherent coagulating media. If, however, on issuing from the coagulating bath, the films contain residual solvent, they may be washed, for example with a salt 55 solution or with dilute solutions of solvents in order to remove such solvent and may then be dried. Preferably however, residual solvent, or at least a small percentage of solvent, for example the last 5 to 10% based on the weight of the material, is removed by evaporation, for ex- 60

ample by passing the films through drying chambers or over heated surfaces.

The drying of the films may take place on the drum or other support on which they are produced or in a separate drying apparatus. In the former case the upper part of the ascending side of the drum may be provided with an enclosing heating segment, which may be heated by steam pipes or in any other suitable manner so that the films are practically completely dried, and they 10 may then be passed to suitable take-up rollers. When drying takes place in a separate apparatus, the films may pass from the drum or other support to the drying apparatus, for example a 15 steam heated drum.

Examples of apparatus which may be employed according to the present invention are illustrated in the accompanying drawing, wherein

Figure 1 shows a cross-sectional elevation of one form of apparatus comprising a drum which 20 is partially immersed in the coagulating medium,

Figure 2 is a cross-sectional elevation of another form of apparatus wherein the drum is completely immersed in the coagulating medium, 25

Figure 3 is a cross-sectional elevation of a portion of a similar apparatus.

Figure 1 illustrates an apparatus comprising a vessel 5 for coagulating medium, a drum 6 which rotates in such medium, and a valve-controlled 30 inlet 7 and an outlet 8 for coagulating medium. The film 9 is extruded through a suitable shaping device 10 connected by means of a pipe 11 with a supply of film-forming solution, and contacts 35 with the drum 6 from which it passes to a roller and thence to suitable washing and drying devices. The shaping device 10 is situated in a casing 12, one side of the casing being formed by an extension of an end of the vessel 5, while the opposite side of the casing extends downward towards the coagulating drum without actually touching the surface of this drum. A hinged flap 13 is fitted in the side of the casing to allow of access to the shaping device.

Figure 2 illustrates a similar form of apparatus 45 comprising a drum 6 rotating in a vessel 5 provided with a valve-controlled inlet 7 and an outlet 8 for coagulating medium. Both inlet and outlet are formed by a slotted or perforated pipe 50 extending across the width of the vessel, so as to obtain a uniform introduction and withdrawal of coagulating medium across the width of the vessel. The film 9 extruded from the shaping device 10, which is situated within a casing 12 and which is connected with the supply of film-forming solution by a pipe 11, contacts with the drum 6 and passes from the drum over a roller to washing and drying devices. The drum 6 is entirely immersed in the coagulating medium, and one side of the casing 12 surrounding the film-forming device is extended downwardly below the surface of the coagulating medium until it almost contacts with the drum. In order to assist circulation of the coagulating medium the portion 65 of this side of the casing below the surface of the coagulating medium may be perforated, or may be formed of metal gauze. Towards the bottom of one side of the casing, but above the level of the coagulating medium, is a shallow vessel 15 which may be filled with solvent liquid in order 70 to maintain the atmosphere in the casing substantially saturated with solvent, and in order to assist in achieving this object a piece of suitable absorbent fabric or other material 16 is suspended from the top of the casing so that its 75

lower edge dips in the solvent contained in the vessel 15. Doors 13 and 14 are fitted to the casing to allow of access to the film-forming device and the vessel 15 and fabric 16.

5 Figure 3 illustrates a detail of a similar apparatus in which means are provided for effecting evaporation of some of the solvent from the film before its entrance into the coagulating medium. As in the other illustrations the apparatus comprises 10 a supply pipe 11 and a shaping device 10, which is situated within a casing 12 and from which the film 9 is extruded, the film contacting with a supporting drum 6. Coagulating medium is withdrawn from the vessel 5 by an outlet pipe 15 18, similar to that described in connection with Fig. 2. An inlet for evaporative medium is provided at 17 and an outlet for such medium at 18, both inlet and outlet being fitted with valves for controlling the flow of evaporative medium.

20 One side of the casing 12 is provided with a door 13 to allow of access to the shaping orifice.

The following example is given in order to illustrate the process of the present invention, but it does not of course limit it in any way:

25 *Example*

A 25% solution of cellulose acetate in acetone is extruded through a shaping orifice contained in a suitable casing, as illustrated, for example, in Figure 2, and after passing for about three inches through the atmosphere contained in the casing it enters a coagulating bath consisting of a 25% aqueous solution of calcium chloride. After passing for about two to four inches through the coagulating bath the film passes round a rotating drum where the coagulation of the film is completed. The film is then washed, first with dilute aqueous calcium chloride solution, for example 5-8%, and then with water, is dried on a steam heated drum, and wound.

While the invention is of particular value in relation to the production of films from solutions of acetone-soluble cellulose acetate, yet it is also of value for the manufacture of such products containing other cellulose acetates or other derivatives of cellulose, for example cellulose formate, propionate, butyrate, nitroacetate or other organic ester or mixed ester of cellulose, cellulose nitrate, methyl, ethyl, butyl or benzyl cellulose or other cellulose ether or mixed ether, and mixed ether-esters, for example ethyl cellulose acetate and oxy-ethyl-cellulose acetate.

55 While particular methods of carrying out the present invention have been described above, it is to be understood that the invention broadly covers the production of films, foils, sheets and the like from solutions of cellulose derivatives, by passing the solutions into coagulating baths from shaping devices which are not in contact with such baths, and also includes the apparatus described in connection with the preferred forms of the invention.

The term "encompassing gaseous medium" as employed hereinafter in the claims is to be construed to mean a gaseous medium which contacts with both sides of the shaped product.

What I claim and desire to secure by Letters Patent is:—

70 1. Apparatus for the manufacture of films, comprising a vessel for coagulating liquid, means for circulating coagulating liquid through such vessel and for maintaining a constant level of coagulating liquid therein, a device having a slot formed therein for shaping the film-forming solution disposed above the level of liquid in said

vessel and adapted to extrude the shaped material first through an encompassing gaseous medium and then into the said liquid, a casing surrounding the shaping device and extending from such device to the surface of the coagulating liquid adapted substantially to isolate the said encompassing gaseous medium from the surrounding atmosphere, and means for introducing the vapor of a liquid into the interior of such casing.

5 2. Apparatus for the manufacture of films, 10 comprising a vessel for coagulating liquid, means for circulating coagulating liquid through such vessel and for maintaining a constant level of coagulating liquid therein, a device having a slot 15 formed therein for shaping the film-forming solution disposed above the level of liquid in said vessel and adapted to extrude the shaped material first through an encompassing gaseous medium and then into the said liquid, a casing surrounding the shaping device and extending from such device to the surface of the coagulating liquid adapted substantially to isolate the said encompassing gaseous medium from the surrounding atmosphere, means for introducing the vapor of a liquid into the interior of such casing, 20 and a rotatable drum positioned at least partially below the liquid level in the vessel for coagulating liquid and adapted to receive and support the shaped material.

25 3. Apparatus for the manufacture of films, 30 comprising a vessel for coagulating liquid, means for circulating coagulating liquid through such vessel and for maintaining a constant level of coagulating liquid therein, a device having a slot 35 formed therein for shaping the film-forming solution disposed above the level of liquid in said vessel and adapted to extrude the shaped material first through an encompassing gaseous medium and then into the said liquid, a casing surrounding the shaping device and extending from such device to the surface of the coagulating liquid adapted substantially to isolate the said encompassing gaseous medium from the surrounding atmosphere, means for introducing the vapor of a liquid into the interior of such casing, 40 a rotatable drum positioned at least partially below the liquid level in the vessel for coagulating liquid adapted to receive and support the shaped material after such material has passed through a portion of the coagulating liquid, and a shield 45 adapted substantially to isolate the portion of the coagulating liquid surrounding the shaped material along its path from the surface of the coagulating liquid to the surface of the drum from the remainder of the coagulating liquid.

55 4. Process for the manufacture of films, which comprises forming a solution of an organic derivative of cellulose into the required shape, passing the shaped product through an encompassing gaseous medium while retarding evaporation 60 of solvent from the shaped product by introducing solvent vapor into said gaseous medium from an external source, and thereafter coagulating the shaped product by passing it into a coagulating bath.

65 5. Process for the manufacture of films, which comprises forming a solution of cellulose acetate into the required shape, passing the shaped product through an encompassing gaseous medium while retarding evaporation of solvent from the 70 shaped product by introducing vapor of said solvent into said gaseous medium from an external source, and thereafter coagulating the shaped product by passing it into a coagulating bath.

6. Process for the manufacture of films, which comprises forming a solution of cellulose acetate into the required shape, passing the shaped product for a distance of 1 to 8 inches through a confined encompassing gaseous medium while retarding evaporation of solvent from the shaped product by introducing vapor of said solvent into said gaseous medium from an external source, and thereafter coagulating the shaped material by passing it into a coagulating bath.
7. Process for the manufacture of films, which comprises forming a solution of cellulose acetate into the required shape, passing the shaped product for a distance of 1 to 8 inches through a confined encompassing gaseous medium while retarding evaporation of solvent from the shaped product by introducing vapor of said solvent into said gaseous medium from an external source, thereafter coagulating the shaped material by passing it into a coagulating bath, and receiving it on a moving supporting surface which is at least partially immersed in said bath.
8. Process for the manufacture of films, which comprises forming a solution of cellulose acetate into the required shape, passing the shaped product for a distance of 1 to 8 inches through a confined encompassing gaseous medium while retarding evaporation of solvent from the shaped product by introducing vapor of said solvent into said gaseous medium from an external source, and thereafter coagulating the shaped product by passing it into a coagulating bath so that coagulating liquid contacts with both sides of the shaped product and then contacting the shaped product with a moving supporting surface which is at least partially immersed in said bath.
9. Process according to claim 8 wherein the portion of coagulating medium through which the shaped product passes before contacting with the supporting surface is substantially separated from the remainder of the liquid.
